UNITED STATES PATENT OFFICE.

HARRY G. BUTLER AND ALBERT F. TEICHMAN, OF CINCINNATI, OHIO, AND EDWARD CARR, OF LUDLOW, KENTUCKY.

CONCRETE MIXER.

Application filed August 1, 1924. Serial No. 729,624.

To all whom it may concern:

Be it known that we, HARRY G. BUTLER, ALBERT F. TEICHMAN, and EDWARD CARR, citizens of the United States of America, 5 and residents of Cincinnati, Cincinnati, and Ludlow, in the counties of Hamilton, Hamilton, and Kenton, and States of Ohio, Ohio, and Kentucky, respectively, have invented a new and useful Improvement in Concrete 10 Mixers, of which the following is a specification.

An object of our invention is to provide means for use with concrete mixers, generally referred to as the side loader type, 15 that will obviate the difficulties and objections heretofore encountered in said devices, in that great difficulty was encountered in discharging the loader bucket whereby the sand, cement and crushed rock is introduced 20 into the drum or mixing barrel.

Another object of our invention is to provide a simple and efficient device for the objects stated.

Another object of our invention is to provide 25 a device that is automatic in performing its work.

These and other objects are attained by the means described herein, and disclosed in the accompanying drawings, in which:

30 Fig. 1 is a slide elevation of a concrete mixer embodying our invention.

Fig. 2 is a sectional view on line 2-2 of Fig. 1.

Fig. 3 is a fragmental plan view of the 35 device embodying our invention.

Fig. 4 is an end view of the device shown in Fig. 3.

Fig. 5 is a side view of an oscillating arm 40 shown in Fig. 4 and forming a detail of our invention.

Our invention as disclosed herein is shown as applied to an arbitrary mixer, for example as shown in the patent to Jaeger #1,390,442 of September 13, 1921, wherefore no detailed explanation thereof will be 45 given.

Briefly the device comprises a frame 10 supporting a revoluble shaft 11 from which a mixing barrel 12 supported by the frame 50 is actuated by means of a ring gear 13 carried by the barrel 12, and a pinion, not shown herein, carried by the shaft 11, and engaging the ring gear 13. The shaft 11 is driven from any suitable source, for example a combustion engine that may be as-

sociated with the frame. The device as disclosed in the said patent to Jaeger comprises a loading bucket 14, that is so supported by the frame 10, that it may be raised and lowered whereby to elevate the end 15, 60 of such bucket for discharging the contents thereof through the chute 16, forming a part of said bucket, into the mixing barrel or drum 12. The bucket 14 is raised and lowered by means of cables 17, that may be wound and unwound by means of spools 18 carried by a shaft 19 driven from the shaft 11 by any suitable means, for example the chain 20, sprockets 21 and 22 and the lever controlled clutch 23. Our invention is concerned with means for vibrating the bucket 14 when it is in its raised or elevated position, whereby to cause the contents of the bucket 14 to expeditiously discharge into the mixing drum 12. 75

As shown herein the bucket 14 may be supported by an intermediate frame of substantially right triangular prismatic form comprising struts 23 and 24 that are pivoted at 25 upon the frame 10. The struts 24 carry a plate 250 that is engaged by a vibrating lug 26. The lug 26 is carried by a shaft 27 mounted upon the frame 10, and said shaft 27 is oscillated by means of an oscillating arm 28 carried by said shaft and which arm has its free or outer end pivotally connected with a rod 29 having an eccentric bearing upon the shaft 11. By reference to Fig. 2, it will be readily evident that when the bucket 14 is moved to its elevated or discharge position, the vibrating lug 26 engages the plate 25 and because of the oscillation of said lug relative to the plate 25, a shocking or jolting action or vibrating action is imparted to the bucket 14, this action serving to precipitate discharge of the contents of the bucket 14 into the drum or barrel. 85

The vibrating lug 26 as shown herein, comprises extensions 30 and 31 disposed at the free end of said lug, the extensions being spaced by a recess or notch 32 extending between the forward faces 33 and 34 of said extensions. It will be readily evident that the notch 32 is not essential and may be dispensed with. 95

It will be observed that the intermediate frame is hinged along one of its acute angled corners to the mixer supporting frame, with its right angled corner upper- 105 110

most, when the prismatic frame is in lowered position, and that the bucket is hinged upon said right angled corner, by means of bars 251. A spring 252 yieldingly retains the bucket upon the intermediate frame. It will be further noted that the vibrating lug operates upon the intermediate frame, and the intermediate frame in turn transmits such vibration to the bucket. The spring 252 yieldingly retains the plate 250 in engagement upon the vibrating lug. Although we have disclosed our invention as applied to a machine as disclosed in the herein mentioned patent to Jaeger, it is to be understood that it is not intended to restrict our invention to this particular type of machine, but that same may be readily applied to other types of mixers, and that modifications may be made in the device invented by us for adapting same to other types of mixers, without deviating from our invention.

In the operation of our device, the lug 30 is oscillated continuously from the shaft 11. The drum 12 operates continuously. Normally the bucket is in its lowermost position, for example as shown in Fig. 1. In this position, workmen deposit sand, cement, crushed rock and the like in the bucket. The bucket is then raised by means of the clutch mechanism 23, shaft 19 and cables 17, whereby to elevate the end 15 of the bucket above the barrel 12 and to dispose the free end of the chute-like extension 16 of the bucket 14, in such position that the contents of the bucket 14 may find their way into the barrel 12. At, or about the time when the bucket 14 reaches its uppermost position, the plate 25 is brought into engagement with the oscillating lug 30. The movement of the lug relative to the plate 25 imparts a series of jolts or vibrations to the bucket 14 that precipitates the contents of the bucket 14 into the drum 12. In Fig. 2 the lug 30 is shown in three positions. In the first position, shown in full lines, the lower end of the extension 31 has moved the plate 250 in a clockwise direction, for a very small distance. Upon the movement of the lug 30 to the second position, shown in dotted lines, and wherein the faces 33 and 34 of the lug engage the face 35 of the plate 25, the movement of the bucket 14 in a clockwise direction is precipitously arrested by contact of the faces 33 and 34 upon 35, and this arresting motion checks the bucket 14, while the contents of the bucket continues its movement because of its impetus, to and into the barrel 12. The movement of the lug to the third position, shown in dotted lines, and wherein the extension 30 alone engages the plate 25 serves merely to again move the bucket in a counter-clockwise direction preparatory to arresting the movement of the bucket in a clockwise direc-

tion for further movement of the contents of the bucket toward the drum 12. It will be readily evident that a very short period of vibration of the bucket 14 is required to discharge the contents thereof, into the 70 barrel 12.

What we claim is:

1. In a device of the class described the combination of a frame, a mixing vessel supported by the frame, means for actuating 75 the mixing vessel, a vibrating lug carried by the frame, and actuated from the vessel actuating means, and a bucket for movement relative to said mixing vessel, and arranged for engagement by the vibrating lug for 80 expediting discharge of the bucket into the mixing vessel.

2. In a device of the class described the combination of a frame, a mixing drum carried by the frame, and having an opening 85 therein, a lug carried by the frame and mounted thereon for oscillation, means for oscillating the lug, a bucket pivotally carried by the frame, arranged to assume a lowermost position for receiving materials 90 to be deposited in the mixing drum, and means for moving the bucket about its pivotal mounting for placing the bucket in position to discharge into the opening in the drum, and for engagement upon the vibrat- 95 ing lug, whereby vibratory motion may be imparted to the bucket for expediting discharge thereof into the mixing drum.

3. The combination with a mixing vessel, a frame for supporting the same and a 100 bucket for the materials to be mixed, of an intermediate frame of substantially right triangular prismatic form hinged along one of its acute angle corners to the mixer supporting frame with its right angle corner 105 uppermost when the prismatic frame is in lowered position and to which the intermediate frame the bucket is hinged along its right angle corner, means for elevating said bucket and intermediate frame, and means 110 whereby the intermediate frame is arrested in its upward movement without arresting the upward movement of the bucket, and arranged for vibrating the bucket.

4. In a device of the class described the 115 combination of a container for treatment of materials, a tiltable bucket for discharging into the container, means for vibrating the bucket when in discharge position, and common means for actuating the container, the 120 bucket and the vibrating means.

5. The combination of a mixer comprising a drum, a tiltable bucket for discharging into the drum, and means for revolving the drum and tilting the bucket, of a vibrating 125 device operative from said means for precipitating discharge from the bucket into the drum.

6. In a device of the class described, the combination with a mixing drum, of a filling 130

- bucket adapted to assume upper and lower positions for respective loading of the bucket and unloading of the bucket into said drum, means for actuating the mixing drum, 5 and for moving the bucket to its upper position, and a vibrator operative from said means for vibrating the bucket in its upper position for expediting discharge of the bucket.
- 10 7. The combination of a mixing vessel, a frame for supporting the vessel, a bucket, a link hingedly connected with both the bucket and the frame, means for elevating both the bucket and the link, said means also 15 adapted to actuate the mixing vessel, means for arresting the upward movement of the link when the bucket and the link are raised without arresting the upward movement of the bucket, and vibrating means for operation on the bucket when in its elevated position for discharging into the mixing vessel, the means for elevating the bucket serving also to actuate the vibrating means.
- 20 8. In a device of the class described, the combination of a frame, a revolving drum carried by the frame, the drum being open
- at its one end, a revolving shaft, means for transmitting rotation from the shaft to the drum, a bucket hingedly mounted on the frame, the bucket comprising an end for receiving substance to be mixed, and a chute 30 for directing substance from said end when elevated, to the opening in the barrel, means operative from the revolving shaft for raising and lowering the bucket, an oscillating 35 lug mounted on the frame, a connection between the revolving shaft and the oscillating lug whereby rotatory motion of the shaft is converted into an oscillatory motion of the oscillating lug, the means for raising and 40 lowering the bucket serving to bring the bucket into position for operation thereon of the lug when the bucket is in an elevated position, and to permit movement of the 45 bucket to its lowermost position wherein the lug is inoperative upon the bucket.

In testimony whereof, we have hereunto subscribed our names this 28th day of July, 1924.

HARRY G. BUTLER.
ALBERT F. TEICHMAN.
EDWARD CARR.
